UNITED STATES PATENT OFFICE.

JOSEPH PRZYGODA, OF PATTON, PENNSYLVANIA, ASSIGNOR OF ONE-THIRD TO IGNATIUS B. ROLKA, OF PATTON, PENNSYLVANIA.

INKSTAND.

No. 907,643.

Specification of Letters Patent.

Patented Dec. 22, 1908.

Application filed April 29, 1908. Serial No. 429,918.

To all whom it may concern:

Be it known that I, JOSEPH PRZYGODA, a citizen of the United States, residing at Patton, in the county of Cambria and State of Pennsylvania, have invented new and useful Improvements in Inkstands, of which the following is a specification.

This invention relates to an ink holder of that type provided with a well or cup that is capable of being adjusted from time to time as the ink is consumed, so as to admit a predetermined quantity of ink in the well into which the pen is dipped, the well serving to prevent the pen from being dipped into the ink too far and also serving to prevent excessive vaporization of the ink from the reservoir.

The invention has for one of its objects to improve and simplify the construction of ink stands of this character so as to be comparatively easy and inexpensive to manufacture, readily adjustable, and composed of few parts.

Another object of the invention is the provision of a dipping well slidably mounted in a bushing and adjustable so as to immerse the lower end thereof into the ink of the reservoir to any suitable depth, the dipping well being readily removable so that it can be cleansed from time to time.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, figure 1 is a central vertical section of an ink stand constructed in accordance with the invention. Fig. 2 is a plan view of the adjusting device for the well.

Similar reference characters are employed to designate corresponding parts throughout the several views.

Referring to the drawing, A designates a reservoir constructed in any suitable form and made of glass, metal or the like, the bottom 1 being provided with a central depression 2, and the top 3 is provided with a neck 4 disposed in line with the depression 2. Fitted in the neck is a compressible bushing 5 of suitable material and slidably mounted in the bushing is the dipping well or cup B

which may be made of a glass or other tube, the lower end being contracted at 6 to form a mouth by means of which the ink feeds from the reservoir into the well, the said mouth being adapted to enter the depression 2 so as to enable the last drop of ink to be utilized when the reservoir is about empty. The exterior of the well B is perfectly smooth and has a sliding fit in the bushing 5, and the upper end of the well is formed with a peripheral flange 7 which limits the inward movement whereby the well can be conveniently gripped in adjusting the same.

On the bushing is arranged a device C for supporting the well in any desired position, the said device consisting of a split ring 8 surrounding the well on the portion thereof extending out of the reservoir, the extremities of the ring being bent outwardly into parallel lugs 9 that are apertured to receive the clamping screw 10. The clamping ring extends around the portion of the bushing 5 that projects out of the neck of the reservoir and clamps the bushing firmly to the cup or well B, the ring resting on the neck to support the well or cup in proper relation to the ink in the reservoir.

In practice, after the reservoir is filled, the well B is inserted in the bushing to such a distance as to submerge the mouth portion of the tube in the ink, and the well is held in this position by adjusting the ring 8 at the proper point on the well. In using the ink stand, the pen is dipped into the well B, the mouth of the latter serving to prevent the pen from being dipped too far into the ink. After the ink in the well is consumed, it is merely necessary to loosen the device C and allow the well to drop farther into the reservoir until the required point is reached, when the device C is again re-clamped. In case it is necessary to remove the well for cleaning the same, the well is lifted out through the bushing 5, as will be readily understood.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such

changes may be made when desired as are within the scope of the claims appended hereto.

Having thus described the invention, what 5 I claim is:—

1. In an ink stand, the combination of a reservoir provided with an opening and an upwardly-extending cylindrical flange at the opening, a bushing lining the flange and ex- 10 tending above the top thereof, a well slidably mounted in the bushing and adjustable vertically therein, a clamping ring disposed around the projecting portion of the bushing, and means for tightening the ring around the bushing to bind the latter to the well.
- 15 2. In an ink stand, the combination of a

reservoir provided with an opening in its top, a well slidably mounted in the opening, a compressible bushing surrounding the well, a clamping ring surrounding the bushing for gripping the latter to the well, said ring being adapted to rest on the top of the reservoir to support the well in adjusted position, and a screw for tightening the ring to engage the bushing.

25 In testimony whereof I affix my signature in presence of two witnesses.

JOSEPH PRZYGODA.
